(73) Assignee: **SEI Optifrontier Co., Ltd.**, Kanagawa (JP)

(57) **CLAIM**

The ornamental design for a pushing part for an optical fiber cutter, as shown and described.

(**) Term: **14 Years**

DESCRIPTION

(21) Appl. No.: **29/402,288**

FIG. 1 is a front view of the pushing part for an optical fiber cutter, showing the new design;

(22) Filed: **Sep. 22, 2011**

FIG. 2 is a rear view of the pushing part for an optical fiber cutter;

(30) **Foreign Application Priority Data**

FIG. 3 is a top plan view of the pushing part for an optical fiber cutter;

Mar. 22, 2011 (JP) D2011-006462

FIG. 4 is a bottom view of the pushing part for an optical fiber cutter;

(51) **LOC (9) CI.** **08-05**

FIG. 5 is a right side view of the pushing part for an optical fiber cutter;

(52) **U.S. CI.**

FIG. 6 is a left side view of the pushing part for an optical fiber cutter;

USPC **D8/51**

FIG. 7 is a top perspective view of the pushing part for an optical fiber cutter;

(58) **Field of Classification Search**

FIG. 8 is a bottom perspective view of the pushing part for an optical fiber cutter;

USPC D8/51, 14, 70.1, 98, 5, 52;

FIG. 9 is a front view of the pushing part for an optical fiber cutter, with a plate lowered;

385/134-137; 30/192

FIG. 10 is a perspective view of the pushing part for an optical fiber cutter, in use; and,

See application file for complete search history.

FIG. 11 is a front view of the pushing part for an optical fiber cutter, in use.
